UNITED STATES PATENT OFFICE.

ERNST F. GRETER, OF MIDLAND, MICHIGAN, ASSIGNOR TO THE DOW CHEMICAL COMPANY, OF MIDLAND, MICHIGAN, A CORPORATION OF MICHIGAN.

METHOD OF PREPARING AMINOPHENOLETHERS.

No Drawing.

Application filed June 2, 1926. Serial No. 113,344.

This invention relates to the preparation of compounds on the order of aminophenol ethers. It has been proposed (German Patent 48,543) to make p-phenetidine by starting with 1 mol. of p-phenetidine, diazotizing and coupling with 1 mol. of phenol, ethylating the resulting compound, and reducing by tin and hydrochloric acid the azophenetol to 2 mol. of phenetidine, of which one was to be carried back into the process. Such procedure has the initial obstacle of starting with expensive phenetidine, and as pointed out by Jacobson and Fischer, Ber. 25, 992, reduction of an azophenetol by tin and hydrochloric acid produces only a small amount of amines, there being instead a predominant decomposition. A procedure of general applicability for making aminophenol ethers is accordingly highly desirable.

To the accomplishment of the foregoing and related ends, the invention, then, consists in the features hereinafter fully described, and particularly pointed out in the claims, the following description setting forth but a few of the various ways in which the principle of the invention may be used.

In accordance with my invention, an arylamine is diazotized, coupled with a phenol, alkylated, and this resulting compound is treated to convert it into an aminophenol ether and the arylamine started with. The particular phenol and alkyl halide used determine the particular aminophenol ether produced. The arylamine employed initially is recovered and may be used over and over again with very little loss.

The course of the reactions involved may be illustrated schematically by the following, in which R and R' represent aryl radicals which may if desired be the same:

As an illustration of the invention, the following is given as an example of the procedure involved, using aniline in this particular instance:

Aniline is treated with sodium nitrite and hydrochloric acid, and coupled with phenol in the proportion of 1 mol. to 1 mol., the resulting compound is treated with ethyl-

bromide, and this product in turn is stirred and heated to a temperature between 50° to 60° C. for about twelve hours with about one-twentieth part (by weight) of iron acetate, three parts of iron, three parts of water, and one part of benzene. Sodium carbonate is then added to precipitate the iron, and the para ethoxyphenylamine (para-phenetidine) and aniline are extracted with benzene and distilled and separated. The benzene used serves to hasten the reaction somewhat, by dissolving the azo compounds and can be replaced by other solvents as toluene, alcohol, etc.

Instead of aniline, o-toluidine or other arylamines can be employed in the process, and likewise other phenols as cresols, naphthols, etc., may be used. Similarly other alkyl halides as methyl bromide, or alkylating agents, as ethyl sulphate, may be employed in lieu of ethyl bromide. In some cases I also contemplate the use of other iron salts, more especially chloride, instead of iron acetate.

The temperature of the final heating is in a sense a reciprocal of the time; that is, the higher the temperature, the shorter the time required. For instance, with a temperature of 70°-80° C., the time required will be only about 5 to 7 hours. However, temperatures as high as 100° C. are prone to cause decomposition, and it is accordingly preferable to operate at lower temperatures.

Other modes of applying the principle of my invention may be employed instead of that here explained, change being made in the features described, provided the steps stated by any of the following claims or the equivalent of such stated steps be employed.

I therefore particularly point out and distinctly claim as my invention:

1. In a method of preparing aminophenol ethers, the steps which consist in diazotizing an arylamine, coupling with a phenol, alkylating, and then reducing by heating with iron and an iron salt in the presence of water.

2. In a method of preparing aminophenol ethers, the steps which consist in diazotizing an arylamine, coupling with a phenol, alkylating, and then reducing by heating with iron and iron acetate in the presence of water.

3. In a method of preparing aminophenoethers, the steps which consist in diazotizing aniline, coupling with a phenol, alkylating, and then reducing by heating with iron and an iron salt in the presence of water. 30
4. In a method of preparing aminophenoethers, the steps which consist in diazotizing aniline, coupling with a phenol, alkylating, and then reducing by heating with iron and iron acetate in the presence of water. 35
5. In a method of preparing aminophenoethers, the steps which consist in diazotizing aniline, coupling with a phenol, alkylating, and then reducing with about one-twentieth part of iron acetate and three parts of iron and one part of water, at a temperature of 50° to 60° C., while stirring. 40
6. In a method of preparing para-phenetidine, the steps which consist in diazotizing aniline, coupling with phenol, alkylating, and then reducing with about one-twentieth part of iron acetate and three parts of iron and one part of water, at a temperature of 50° to 60° C., while stirring. 45
7. In a method of preparing aminophenoethers, the steps which consist in diazo-
- tizing an arylamine, coupling with a phenol, alkylating, and then reducing by heating with iron and an iron salt, in the presence of water and an organic solvent unreactive with the mixture components. 50
8. In a method of preparing aminophenoethers, the steps which consist in diazotizing aniline, coupling with a phenol, alkylating, and then reducing by heating with iron and an iron salt in the presence of water and an organic solvent unreactive with the mixture components. 55
9. The method of preparing para-phenetidine, which comprises diazotizing aniline, coupling with phenol, alkylating, and then reducing with iron and an iron salt in the presence of water and an organic solvent unreactive with the mixture components, at a temperature below 100° C. 60
10. A method of preparing para-phenetidine, which comprises diazotizing aniline, coupling with phenol, alkylating, and then reducing with iron and an iron salt in the presence of benzene at a temperature below 100° C. 65

Signed by me this 27th day of May, 1926.

ERNST F. GRETHER.
